DESIGN FOR A BOX OR SIMILAR ARTICLE

Bernard Lamotte, New York, N. Y., assignor to Pinaud Incorporated, New York, N. Y., a corporation of New York

Application February 24, 1945, Serial No. 118,122

Term of patent 14 years

(Cl. D58—11)

To all whom it may concern:

Be it known that I, Bernard Lamotte, a French citizen and a resident of the city, county, and State of New York, have invented a new, original, and ornamental Design for a Box or Similar Article, of which the following is a specification, reference being had to the accompanying drawing forming a part thereof.

Fig. 1 of the drawing is a perspective view of two sides and the top of a box showing my new design;

Fig. 2 is a similar perspective view of the other two sides and the top of the box shown in Fig. 1.

I claim:

The ornamental design for a box or similar article, as shown.

BERNARD LAMOTTE.
